DESIGN FOR A SHOE

Arthur H. Tupper, New York, N. Y.

Application July 18, 1935, Serial No. 57,707

Term of patent 3½ years

To all whom it may concern:

Be it known that I, Arthur H. Tupper, a citizen of the United States, residing at New York, in the county of New York and State of New York, have invented a new, original, and ornamental Design for a Shoe, of which the following is a specification, reference being had to the accompanying drawing, forming part thereof.

Figure 1 is a plan view of a shoe, showing my new design; and Figure 2 is a side elevation of the same.

The dominating features of applicant's design are the strap above the instep with its lower end cut in a U-shaped formation to which portion are

attached the two sharply pointed ends of the triangular shaped elements at each side of the forepart of the shoe and the sharply pointed end of the single triangular shaped element at the toe portion of the shoe, and the tapering strap which crosses over the said U-shaped portion of the above mentioned strap, the said strap being narrowest in the center and gradually widening where it is attached to the sole of the shoe.

I claim:

The ornamental design for a shoe, substantially as shown and described.

ARTHUR H. TUPPER.
